Primary Examiner — Karen E Eldridge Powers*Assistant Examiner* — Margaret Leah Bryan(74) *Attorney, Agent, or Firm* — Sandy Lipkin(57) **CLAIM**

The ornamental design for a nail drill machine, as shown and described.

DESCRIPTION

FIG. 1 is a front view of a nail drill machine, showing my new design;

FIG. 2 is a top plan view thereof;

FIG. 3 is a bottom plan view thereof;

FIG. 4 is a rear plan view thereof;

FIG. 5 is a left plan view thereof; and,

FIG. 6 is a right plan view thereof.

The broken lines in the drawings depict portions of the nail drill machine that form no part of the claimed design.

1 Claim, 6 Drawing Sheets(56)
